(57) **CLAIM**

The ornamental design for a mounting system, as shown.

DESCRIPTION

FIG. 1 is a top perspective view of a mounting system, showing our new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is top plan view thereof;

FIG. 7 is a bottom plan view thereof;

FIG. 8 is another top perspective view thereof;

FIG. 9 is a top perspective view of two of the mounting systems of FIG. 1, with one the mirror-image of the other, shown in an example environment;

FIG. 10 is a left side elevation view thereof; and,

FIG. 11 is another top perspective thereof.

The broken lines shown in the drawings are for illustrative purposes only and form no part of the claimed design.
